(57) **CLAIM**

The ornamental design for a curved drain board, as shown and described.

DESCRIPTION

The invention is a device for receiving and draining water from dishes.

FIG. 1 is a front perspective view of a curved drain board showing my new design;

FIG. 2 is a bottom perspective view thereof;

FIG. 3 is a front elevation view thereof;

FIG. 4 is a rear elevation view thereof;

FIG. 5 is a right side elevation view thereof and it is the

mirror image of the left side elevation view;

FIG. 6 is a top plan view thereof; and,

FIG. 7 is a bottom plan view thereof.
